WINDOW OPERATING MECHANISM

Richard W. Treverton, Buffalo, N. Y., assignor
to Trico Products Corporation, Buffalo, N. Y.

Application October 15, 1941, Serial No. 415,104

9 Claims. (Cl. 268—125)

The present invention relates to windows and operating mechanisms therefor and has particular relation to such mechanisms of this kind operated by fluid pressure and other power devices.

Heretofore window operators, used on motor vehicles, have comprised various power actuated devices including those utilizing suction available in the intake manifold of the engine or other source of less-than-atmospheric pressure, to raise and lower the windows, the devices being controlled by suitable means. In the case of suction operators, in order to prevent the unauthorized forcing opening of windows, means have been provided to prevent movement of the windows except under the influence of suction.

It is desirable not to apply such locking means to prevent movement in the opposite direction, since it may be wished to close a window at times when the fluid pressure differential or other source of power is not available, as for example it may be desired to close the window of an automobile when the engine, depended upon as the source of power, is not running, and perhaps cannot be run by reason of some mechanical defect or the like.

Ordinarily, however, the windows of a vehicle when fully opened are in the well of the door below or so close to the sill that they cannot be gripped with the fingers so as to be raised manually. It is an objective of the present invention to overcome this difficulty; to provide means for raising a window slightly, so that it may be engaged and raised by the hands at time when no power is available to raise the window.

These and other objects and advantages will appear from the following description of the typical embodiment of the invention shown in the accompanying drawing, wherein:

Fig. 1 is a side elevation of the window, window actuator, and control therefor;

Fig. 2 is an elevation, partly in section, of the valve unit employed to control the actuator, with parts appearing in section; and,

Fig. 3 is a detail view of a valve actuating element.

As shown in Fig. 1 the window 11 in fully opened position is in the window well formed by the inner and outer surfaces of the body or door and may have its upper edge even with or slightly below sill 12 on the bottom wall of the window opening. The actuating means may comprise a cylinder 13 hinged at 14 to a stationary part of the structure having the window opening, a piston 15 movable in the cylinder being effective through piston rod 16 to swing bell

crank lever 17 about the latter's pivot 18. The bell crank carries a roller 19 engaged in a track 21 secured to the lower edge of the window, so that upon counter-clockwise movement of the bell-crank (movement of piston 15 to the right) the window will be raised or closed, and upon subsequent clockwise movement of the bell-crank, the window will again be opened.

For operating the suction actuated device a pair of conduits 22 and 23 are extended from the ends of cylinder 13 to a valve body 24 containing valves which normally open communication between both conduits 22 and 23 and a conduit 25 which extends from the body to a source of suction, such as the intake manifold of an internal combustion engine. Each of the valves, which may be of any suitable type, such as the construction shown in said application of Anton Rappi, Serial No. 383,176, may have a spring backed, manually depressible push button having a stem 28 provided with parts 29 for engaging the valve, the valves being so arranged that depression of upper push button 26 may break fluid communication between conduit 23 and the source conduit 25 and open conduit 23 to the atmosphere, while depression of the lower push button 27 will shut off conduit 25 from conduit 23 and will open the latter to the atmosphere.

Accordingly when suction is available in conduit 25 depression of button 26 will cause the window to close, while depression of button 27 will effect opening movement of the window. As indicated hereinbefore, the piston 15 may be of the type disclosed in said application Serial No. 383,176, being provided with a lock 31 to prevent opening movement of the window, i. e., movement of the piston to the left in Fig. 1, except when differential pressures are acting upon opposite faces of the piston: suction from conduit 22 and atmospheric pressure from conduit 23. However, the piston may in the absence of any pressure differential be moved by an extraneous force in the opposite direction, to the right in Fig. 1.

In order to bring the window partially out of the well and above sill 12 within the grasp of the hands so that it may be raised manually, a spring 41 is disposed between a fixed abutment member 42 and head 43 of a rod 44, the latter in the illustrated embodiment being mounted for sliding movement in member 42 and valve body 24, and the head 43 engaging an extension 45 of the bell crank 17 under pressure of the spring. For preventing the spring 41 from always raising the window 11 to the broken line position in Fig. 1

when pressures on the opposite faces of piston 15 are equalized, latch or clutch means are provided to hold the rod 44 against downward movement except when the up valve button 26 is depressed. Such means may comprise wedge blocks 46 engaging the rod and inclined or conical side wall portions 47 of the valve casing or body 24, being pressed thereagainst by a spring 48 backed by a cap 49 secured to the casing 24. A part 51 having an inclined or cam face 52 extends from the actuator stem 28 of the "up" button 26, the inclined face being engageable with the end faces of blocks 46, to move the latter against the compression of spring 48, when the button is pressed.

In operation, when the "down" button 27 is pressed, and the power unit 13, 15 is operative to swing lever 17 clockwise, lowering the window into the well, the latch mechanism just disassembled will not interfere with such action. This is for the reason that such action raises rod 44, and any clutching of blocks 46 to the rod will result in their release, since as they move upwardly the divergence of walls 47 allows them to separate. Also when the "up" button 26 is pressed and the power unit 13, 15 is operative to raise the window, the cam 51 will be effective to release the clutch or latch blocks, so that the window may be raised to any desired degree by the cylinder and piston power means. The latch mechanism is effective when the window is in fully lowered position or nearly fully lowered position, and neither button is being pressed, to prevent the spring 41 from raising the window to the broken line position of Fig. 1. When, however, the power unit 13, 15 is ineffective and it is desired to raise the window, pressing button 26 will result in release of the latch mechanism allowing spring 41 to raise the window to a position partially out of the well and above the sill so that it may be engaged by the hands and be moved manually to closed position or other raised position.

It will be understood that the window and operating mechanism may be of any suitable construction, including suitable counterbalancing means, if desired. The present invention provides spring means for initiating movement of the window from one terminal position, from opened position in the form shown, which may be especially advantageous in the case of a window that is not fully counterbalanced.

It will be understood further that the apparatus herein shown and described is merely illustrative of the inventive principles involved, and that the same may be otherwise embodied without departing from the spirit of the invention or the scope of the appended claims.

What is claimed is:

1. In a window construction and operating means therefor, a framing structure having a well and a window slidably therein between an opened position in the well and a closed position, fluid pressure operated means for moving the window between said positions, spring means compressed as the window approaches fully opened position for urging initial opening movement of the window to a point above the well, spring pressed latch means effective to hold the window against such motion by the spring means, and manually operated means for releasing the latch means.

2. In a window construction and operating means therefor, a framing structure and a window slidable therein between opened and closed

positions, fluid pressure operated means for moving the window between said positions, spring means compressed as the window approaches fully opened position for urging initial closing movement of the window, latch means effective to hold the window against such motion by the spring means, control means for the fluid pressure operated means including a member manually movable to normally cause closing movement of the window, and means effective upon such manual movement of said member to release said latch means.

3. In a window construction and operating means therefor, a framing structure having a well formed by opposing walls and a window slidably movable therein between opened and closed positions, power operated means for moving said window between said positions including manually operated control means, spring means for raising the window out of the well to a partially closed position, clutch means acting on said spring means for normally holding it against operation to so initiate movement of the window, and means effective upon operation of the control means to release the holding means whereby said spring means will coact with said power means for closing the window.

4. In a window construction and operating means therefor, a framing structure and a window slidably movable therein between an opened position completely within said structure and a closed position, power operated means for moving the window between said positions, spring means compressed as the window approaches one terminal position for urging reverse movement thereof upon subsequent expansion of the spring, means for preventing such expansion of the spring from a compressed condition, a control element for the power operated means, and joint means effective upon actuation of said control element to release said spring for expansion to raise the window above the sill should the power means fail to function.

5. In a window construction and operating means therefor, a framing structure comprising a well and an opening and a window slidably movable therein between opened and closed positions, power operated means for moving the window, and spring means held compressed by clutch means upon the window reaching a terminal position for subsequent expansion upon its release to initiate movement of the window from said terminal position to a position exposing a portion for manual operation whereby completion of the movement may be effected by hand.

6. In a window construction and operating means therefor, a framing structure having a well and a sill and a window slidably movable therein between opened and closed positions, power operated means for moving the window, and spring means compressed upon the window reaching an open position for subsequent expansion to initiate movement of the window from said open position to a position slightly above the sill upon failure of the power means, means for normally holding said spring against such expansion, and means for releasing said holding means.

7. In a window construction and operating means therefor, a structure comprising a well and a frame and a window slidably movable therein between an opened position within the well and a closed position in the frame, power operating means for the window, spring means compressed upon the window reaching an open position, a clutch permitting compressive move-

ment of the spring means while holding the spring against expansion, and means to release said clutch to allow expansion of the spring from compressed position to initiate movement of the window from said open position to a position where a part of the window is raised out of the well and is exposed in the frame sufficiently to be manually operated to complete the closing.

8. In a window construction and operating means therefor, a framing structure and a window slidably movable therein between opened and closed positions, power operated means for moving the window, spring means compressed upon the window reaching a terminal position for subsequent expansion to initiate movement of the window from said terminal position, means for normally holding said spring against such expansion, said means comprising a spring pressed rod mounted for slidable movement in a fixed portion of the structure, a pair of spring

pressed clutch members for holding the rod normally against slidable movement in one direction, cam means for releasing the clutch members to allow slidable movement, and means for releasing said holding means.

9. In a window construction and operating means therefor, a framing structure having a well and a window slidable therein, fluid pressure operated means for moving the window between an open position in the well and a closed position relative to said framing structure, means for controlling said fluid pressure operated means, spring means operable for urging initial closing movement of the window out of the well, and latch means releasably holding said spring means inoperative and operable to release such spring means to so function when the fluid pressure operated means fails to operate.
